UNITED STATES PATENT OFFICE.

FRANK G. STARK, OF ST. LOUIS, MISSOURI, ASSIGNOR TO THE CARBO-
ALUMINA METAL COMPANY, OF SAME PLACE.

DESIGN FOR A BICYCLE-FRAME.

SPECIFICATION forming part of Design No. 23,395, dated June 19, 1894.

Application filed January 8, 1894. Serial No. 496,208. Term of patent 14 years.

To all whom it may concern:

Be it known that I, FRANK G. STARK, a citizen of the United States, residing in the city of St. Louis, State of Missouri, have invented and produced a new and original Design for Bicycle-Frames, of which the following is a full, clear, and exact description, reference being had to the accompanying drawings, wherein—

Figure 1 represents a perspective view of a bicycle frame made according to my new and original design. Fig. 2 is a cross sectional view through one of the brace rods, illustrating the shape thereof in cross section.

This design has relation to the configuration and shape of the frame of a bicycle.

The upper front brace rod, the lower front brace rod, and the rear forks, are grooved

longitudinally, leaving a flange or bead at the upper and lower edges thereof, the cross section of which rod is illustrated in Fig. 2.

The steering head and center post are cylindrical in cross section, the steering head being ornamented at its upper and lower extremities with annular beads or enlargements.

What I claim is—

The design for a bicycle frame, substantially as herein shown and described.

In testimony whereof I hereunto affix my signature, in presence of two witnesses, this 29th day of December, 1893.

FRANK G. STARK.

Witnesses:

HUGH K. WAGNER,
W. M. BYRNE.
